J. McNAMARA,
PRESSURE REGULATOR,
APPLICATION FILED MAR. 20, 1919.

Patented Apr. 6, 1920.

INVENTOR

JAMES McNAMARA

BY

Edward B Birkenbeul.
ATTORNEY

UNITED STATES PATENT OFFICE.

JAMES McNAMARA, OF PORTLAND, OREGON.

PRESSURE-REGULATOR.

1,335,903.

Specification of Letters Patent. Patented Apr. 6, 1920.

Application filed March 20, 1919. Serial No. 283,925.

To all whom it may concern:

Be it known that I, JAMES McNAMARA, a subject of the King of Great Britain, (who has declared his intention of becoming a citizen of the United States,) residing in the city of Portland, in the county of Multnomah and State of Oregon, have invented a new and useful Pressure-Regulator, of which the following is a specification.

- 10 My invention relates more particularly to a means for reducing and regulating the pressure of gas which is being delivered from a pressure tank to a cutting or welding torch.
- 15 The object of my invention is to provide an exceedingly simple and efficient means for reducing and regulating gas pressures, which will be easy to manufacture, not liable to injury from rough handling, easy to repair, and absolutely accurate in regulation over a wide range of pressures.

I attain these object in the manner illustrated in the accompanying drawing, in which—

25 Figure 1 is an end elevation with a portion cut away in section along the line 1—1 in Fig. 2; Fig. 2 is a broken section through stuffing box and high pressure inlet and in front of working parts; Fig. 3 is a plan shown in section along the line 3—3 in Fig. 1; Fig. 4 is a section along the line 4—4 in Fig. 2; Fig. 5 is a partial plan showing the indicator and graduations.

30 Similar numbers and letters of reference refer to the same or similar parts throughout the several views.

The gas tank A¹ and the torch A² represent the usual appliances which are in common use in the art.

40 Referring directly to my device, the frame F¹ is the central portion of a hollow cylinder. Along the bottom edge of F¹ is the threaded flange F². Around the inside of frame F¹ and near its top is the ledge F³ which supports the glass cover plate F⁴, over which is placed the packing F⁵, which is held down by the perforated guard F⁶. On the glass F⁴ are the graduations F⁷ which may vary to suit the peculiar requirements 45 of the individual regulator. F⁸ is the ordinary safety valve which is screwed into the side of the frame F¹.

50 The tank pipe H¹ delivers the gas, which is under a high and variable pressure, to the regulator and is screwed into the receptacle

H². The end of the tank pipe is formed into the tip H³. H⁴ is the tapped central core of the receptacle H². H⁵ is the gas space which is formed around the core H⁴. Inside of the core H⁴ is the bracket H⁶, 60 whose hole H⁷ carries the plunger H⁸, whose head H⁹ contains the fiber valve seat H¹⁰. H¹¹ is the low pressure outlet.

On the under side of the threaded flange F² is placed the diaphragm K¹, upon which 65 is mounted the bracket K² whose threaded shank K³ passes through the diaphragm and is secured thereto by the nut K⁴. Beneath the nut K⁴ is the compression spring K⁵ which is held in place by the threaded 70 spring retainer K⁶, which screws into the cap K⁷ on the flange F². K⁷ also serves to hold the diaphragm K¹ in place and is perforated at K⁸ to balance the pressure on both sides of the cap K⁷. 75

L¹ is a stuffing box which is closed by the gland L² whose stem is the regulator screw L³ of which the shoulder L⁴ is able to exert an end thrust on the packing. L⁵ is a thumb nut for rotating the screw L³. The screw 80 L³ enters the frame F¹ by way of the hole L⁶ and journals in the farther side of the frame F¹ in the hole L⁷.

Inside of the frame F¹ are the lower bosses M¹ in which are located the holes M² 85 in which is the pin M³, upon which is mounted the hinged slide M⁴ whose upper portion is dove-tailed at M⁵. Lugs M⁶ are formed on the lower side of the hinged slide M⁴ and are joined to the bracket K² by the 90 pin M⁷. On the dove-tailed portion M⁵ is mounted the crosshead M⁸ whose arm M⁹ has the opening M¹⁰.

The bell crank lever O¹ has a horizontal limb O² and a vertical limb O³. Its fulcrum 95 is located at the hole O⁴ and consists of the pin O⁵ which is carried by the upper bosses O⁶ in the holes O⁷.

R¹ is the regulator carriage which is tapped to ride on the screw L³. From the 100 carriage R¹ project the forks R² and the indicator arm R³ which moves along on the under side of the graduated glass F⁴.

It will be seen that any gas escaping from the tip H³ and does not escape through the 105 outlet H¹¹ will exert a pressure on the diaphragm K¹ compressing the spring K⁵ and depressing the bracket K², which in turn draws downward the crosshead M⁸ through whose opening M¹⁰ passes the limb O² of the 110

- bell crank lever O^1 , whose limb O^3 now exerts a pressure against the plunger H^8 and forces the valve seat H^{10} against the tip H^3 , thereby cutting off the flow of gas. It is evident that by operating the thumb nut L^5 the carriage R^1 will be moved along the screw L^3 , and its fork R^2 will move the arm M^9 along the limb O^2 thereby changing the leverage directed against the plunger H^8 .
- 10 It will also be seen that by converging the longitudinal axes of the limb O^2 and the slide M^4 , that a greater rapidity of adjustment is secured than would otherwise be possible.
- 15 By supporting the plunger H^8 from one wall of the opening H^4 , I avoid the bad effects of expansion and contraction and, by jacketing the point at which the high pressure gas escapes, the freezing action is practically eliminated.
- 20 While I have thus described my invention, it is not my desire to limit my invention to this precise form or method of application, but intend that it shall cover all forms and modifications that fall fairly within the appended claim.

What I claim as new and desire to protect by Letters Patent of the United States, is:

In a pressure regulator the combination of a gas chamber having a high pressure inlet valve and a regulated pressure outlet with a valve regulating mechanism, consisting of a diaphragm arranged to form the bottom of said gas chamber, a perforated cap adapted to hold said diaphragm in place, a spring placed between said cap and diaphragm, in a manner to return said diaphragm to its original position when the contained pressure is reduced, a knuckle member secured upon said diaphragm, a guide hinged inside of said chamber and joined to said knuckle, a slide mounted on said guide having an eye at its upper end, a forked nut adapted to engage said slide, a screw adapted to move said nut and be operated from the exterior of said chamber, a bell crank lever adapted to enter the eye of said slide and be actuated thereby and having its other arm arranged to actuate said high pressure inlet valve.

JAMES McNAMARA.
